UNITED STATES PATENT OFFICE.

CHARLES JOHN ARMSTRONG, OF AUSTIN, TEXAS, ASSIGNOR TO TIPS ENGINE WORKS,
OF AUSTIN, TEXAS.

DESIGN FOR A COVER FOR WATER-METER BOX.

Application filed May 12, 1925. Serial No. 13,419. Term of patent 3½ years.

To all whom it may concern:

Be it known that I, CHARLES J. ARMSTRONG, a citizen of the United States, residing at Austin, Texas, in the county of Travis and State of Texas, have invented a new, original, and ornamental Design for a Cover for Water-Meter Boxes, of which the following is a specification, reference being had to the accompanying drawing, forming part thereof.

Figure 1 is a plan view of a cover for water meter boxes showing my new design.

Figure 2 is a side view thereof.

What is claimed is:

The ornamental design for a cover for water meter boxes, as shown.

CHARLES JOHN ARMSTRONG.
